UNITED STATES PATENT OFFICE.

ARTHUR K. TAYLOR, OF BALTIMORE, MARYLAND.

SHEET-DRIER.

SPECIFICATION forming part of Letters Patent No. 728,329, dated May 19, 1903.

Application filed December 17, 1902. Serial No. 135,822. (No model.)

To all whom it may concern:

Be it known that I, ARTHUR K. TAYLOR, a citizen of the United States of America, and a resident of the city of Baltimore, State of Maryland, have invented certain new and useful Improvements in Sheet-Driers, of which the following is a specification.

This invention relates to improvements in machines for drying sheets of paper as they are delivered from a printing or similar machine, and it is especially adapted to receive the sheets as they are delivered from a printing-press to allow the ink time to dry before the sheets are piled up.

It is a well-known fact that rapid printing is frequently of little value in certain lines of work, owing to the fact that because of the rapidity with which the sheets are delivered onto the pile the ink does not have time to dry, and consequently offsets onto the adjacent sheet and also smears. My invention is designed to overcome this difficulty by providing an apparatus which is adapted to be placed in position adjacent to the delivery end of a press and receive the sheets from the delivery mechanism of the press and hold them separated from each other until they have had time to dry and after they are thoroughly dried placing them on a pile from which they can be readily removed by the press attendant. This I accomplish by delivering each sheet on a separate receiving surface or shelf, the receiving surfaces or shelves being so operated that they will successively come into position to receive the sheet as it is delivered from the press and carry it to the point where it is finally delivered, the sheets during this time being kept entirely separate from each other.

The object of my invention is to provide in a drier a pile of pliable shelves which are operated by appropriate mechanism and which are stripped from under the sheet to deliver the sheet therefrom, and after they are withdrawn from under the sheet they are carried to a position where they receive a freshly-printed sheet. During the time the shelves are carrying the sheets they are superimposed, forming a pile, the sheet-carrying surfaces, of the shelves being spaced apart to prevent contact with the freshly-printed surfaces and the pile is moved down

by degrees, the lowermost shelf of the pile being the one from which the sheet is delivered by withdrawing the shelf from under the sheet, the shelf as soon as it is withdrawn being carried to the top of the pile to receive a fresh sheet. By this means it will be seen that a sufficient length of time is given to the sheets to thoroughly dry before they are piled in contact with one another.

To carry out the operations above enumerated, certain details of construction and peculiar arrangement of parts have been provided, and to this end my invention also contemplates certain improvements in the mechanism for carrying out these operations, all of which will be hereinafter described and then particularly pointed out in the claims.

Referring to the drawings, wherein like parts are designated by the same reference-numerals wherever they occur, Figure 1 is a side elevation of my improved drying apparatus, also showing part of the connections between the drying apparatus and a printing-press by which the sheets are delivered from the press to the drier. Fig. 2 is an end view of the drier partly broken away, to more clearly show the construction. Fig. 3 is an inside view of one of the side frames. Fig. 4 is a detail view of the escapement mechanism by which one end of the pile of shelves is normally supported and by which one end of the lowermost shelf is separated from the pile, the parts being shown in their normal position. Fig. 5 is a view similar to Fig. 4 with the escapement shown in the act of separating the bottommost shelf from the pile. Fig. 6 is a detail view of the escapement which supports the other end of the pile of shelves and separates that end of the bottommost shelf from the pile. Fig. 7 is a sectional view on line $\alpha\alpha$ of Fig. 6. Fig. 8 is an enlarged detail view of the operating mechanism for the delivery-tables onto which the sheets are delivered by the press and from which they are passed into the drier. Fig. 9 is a detail top plan view of the delivery-tables. Fig. 10 is a detail side elevation of one of a pair of switches, showing the switch in its normal position by which the roll of the topmost shelf when placed in position is admitted to and held in the vertical channel. Fig. 11 is a similar view illustrating the operation of

the switch admitting a roll to the vertical channel. Fig. 12 is a detail sectional view on line $y-y$ of Fig. 10. Fig. 13 a detail view of one of the shelves. Fig. 14 is a sectional view of the carriage and spring-roller by which the shelves are held taut while they are removed from the bottom of the pile. Fig. 15 is a detail view showing the end of the carriage shown in Fig. 14.

10 Referring particularly to Figs. 1 and 2, 1 represents a pair of frames, each consisting of the upper bars 2, the lower bars 3, the front bars 4, and the rear bars 5. Each of these frames is in substantially the form of a 15 rectangle, and the pair of frames are suitably braced together by the cross-braces 6. Preferably these frames are mounted on wheels or rollers 7, whereby it is easy to place the drier in position to receive the sheets as they 20 are delivered from the printing or other machine. Referring particularly to Fig. 3, it will be seen that the frames which are duplicates of each other have a continuous slot or channel cut through the four sides thereof, 25 this channel being formed of the portion 8 in the bar 4, the portion 9 in the bar 5, the portion 10 in the bar 3, and the portion 11 in the bar 2. The four portions of this channel are connected together by suitably-curved 30 portions and at the upper rear corner by the inclined portion which is formed by the inclined sides 12 and 13. Yokes 14 surround the channel or slot at intervals and are preferably cast integral with the frame. 35 These are necessary in order to support the inner portions of the frame. In each of the front bars 4 I provide an endless groove or channel 15, which is composed of two channels or grooves 16 17, which meet at 40 their upper end and slightly diverge toward their lower end, the lower ends of these channels being connected by the channel or groove 18, which is wider than the channels 16 17 and is curved, as best shown in Fig. 3. 45 19 is a channel cut in the lower side of each of the frames and inclined from the front to the rear of the frame, as best shown in Figs. 1 and 3. These channels are each provided on their upper side with a rack 20, and in the 50 channels 19 is mounted a carriage carrying a roller which holds the flexible portion of a sheet taut while it is being withdrawn from the bottom of the pile, to be hereinafter described. 55 21 is a switch pivoted on the stud 22, mounted on the outside of each of the frames 1 adjacent to the portions of the slot or groove formed by the beveled sides 12 and 13. Each switch is so mounted that when it 60 is in its normal position (shown in Fig. 10) the free end of the switch will be in contact with the beveled portion 12 of the slot, the beveled portion 12 projecting out from the face of the frame sufficiently far to form a 65 stop for this purpose. When the switch is in its normal position, its upper edge is in an aline-

ment with the lower wall of the portion 11 of the slot.

23 represents springs, one for each switch, mounted on the studs 22 and having one end 70 connected to the switch and the other end connected to the frame adapted to normally hold the switch with its free end in contact with the beveled face 12. When the switch is depressed, as shown in Fig. 11, the upper 75 edge of the switch will be in alinement with the lower incline 13 of the slot.

24 represents a shelf comprising end rods 25 and 26 and the pliable connecting portion 27, these parts being so connected and positioned that when the shelf is stretched the portion 27 extends directly from the center of its supporting-rods in the manner best shown in Fig. 13. The portion 27 is somewhat narrower than the rods 25 and 26, so that the latter project out at each end and may travel in the slots of the side frames in the manner to be hereinafter described. A number of these shelves are used in the operation of the machine, as is clearly shown in the drawings, the 90 shelves being held in the frame in a pile, with the ends of the rods 25 projecting into the slot formed by the portions 8, 9, 10, and 11 and the ends of the rods 26 projecting into the slot formed by the portions 15, whereby, as will 95 be seen, the rods 25 may travel in a substantially rectangular path around the frame, while the rods 26 will travel only up and down one side of this rectangle and on the interior of the rectangle. As best shown in Fig. 1, I 100 provide such a number of shelves that the rods 26 will fill the portion 17 when one of the rods is out of this portion, since in the operation of my device one of the rods is always out of the portion 17, because a rod is taken from the bottom of the pile as soon as another rod has been placed in position at the top of the pile, it being understood that the rods carrying a shelf are removed from the bottom of the pile to deliver the dried sheets and are then carried to 110 the top of the pile and placed in position to receive a fresh sheet. At the lower rear end of each of the portions 9 of the slots I provide a pair of escapement devices 29, (shown in Figs. 4 and 5,) which are adapted to separate the rod 26 of the shelf, which is at the bottom of the pile, from the remaining rods in the pile to allow the shelf to deliver the dried sheet and then be removed to its position at the top of the pile, where it may receive a fresh sheet, the escapement devices operating to prevent more than a single rod at a time being transferred from the slot 8 to the slot 10 and holding the remaining rods in position in the slot 8. It is to be understood 115 that there is an escapement on each of the side frames to act on both ends of a rod; but as the pair of escapements are duplicates of each other but one will be described.

Mounted on the stud 28, which projects out 120 from the guard 14 on each of the side frames, is the escapement device 29, which is in the

form of a pair of legs 30 31, the leg 30 being provided at its end with a toe 32, which when the escapement is in its normal position, as shown in Fig. 4, is adapted to support the pile 5 of rods in the slot 9. The leg 31 is widened at about its middle portion and forms a shoulder 33, and at the inner end of this shoulder is a toe 34. The end of the toe 34 is located in a plane which is a distance above the plane 10 of the end of the toe 32 equal to the diameter of a rod, so that when the escapement is swung to the position shown in Fig. 5 the toe 34 will enter just above the bottom rod in the slot. The leg 31 is provided below the toe 34 15 with a camming-face 35, which is adapted, should a rod stick in the slot, to force the rod down around the curve into the portion 10 of the slot.

36 is a spring, one end of which is connected 20 to the leg 31 and the other end secured to the frame and adapted to hold the escapement in the position shown in Fig. 4.

Mounted on the side frames adjacent to the slots 17 are another pair of escapements, 25 (shown in Figs. 6 and 7,) which operate to support the pile of rods 25 in the slots 17 and at a proper time are operated to separate the lowermost rod from the pile and allow it to pass into the portion 18 of the slots. As these 30 escapements are duplicates of each other and operate together, one on one end of a rod and the other on the other, I will describe but one, and it will be understood that the description also applies to the other.

35 37 is a plate which is preferably formed integral with the frame and is adapted to support the escapement, which is located in proximity to the lower end of the slot 17, and 38 is a plate secured to the plate 37 by the bolts 40 and suitably spaced therefrom by means 45 of spacing-collars 125 on the bolts.

40 is a lever, one end of which is pivoted on the stud 41, projecting from the plates 37. This lever is provided at its lower end with 45 the notch 42, which is adapted to be engaged by a suitable part to be hereinafter described.

43 and 44 are a pair of dogs, which are mounted between the plates 37 and 38 and are guided by projecting shoulders 45 and 46, 50 which project into channels 47 and 48, cut in the inner face of the plate 38.

49 is a lever pivoted on the stud 50, projecting out from the plate 38, the upper end of this lever having an elongated hole 51, 55 through which passes a stud 52, carried by the lever 40. The lever 49 is provided at its other end with an elongated hole 53, into which projects a stud 54, carried by the dog 44, the pin projecting through a suitable 60 opening 55, cut in the plate 38.

56 is a plate, preferably formed integral with the dog 43 and is provided with an elongated hole in its upper end similar to the hole 51, into which also projects the stud 52. The 65 forward ends of the dogs 43 44 are beveled at 57, and the distance between the top of the dog 44 and the top of the dog 43 is such that

the upper beveled end of the dog 43 will enter above a rod, which is supported upon the top of the dog 44, as is clearly shown in Fig. 6. 70

Referring to Fig. 1, 59, 60, 61, and 62 are four pairs of sprocket-wheels, one of each pair being mounted at each of the corners of each frame. The sprockets 59, 60, and 62 are mounted on stub-shafts, while the sprockets 75 61 are mounted on the shaft 92, which is mounted in bearings in the side frames. 58 58 are two chains, one of which runs over each of the sets of sprockets. Preferably and as shown the stub-shafts for the sprocket-wheels 80 59 are each mounted on a plate 63, and this plate may be adjusted on the frame by means of the elongated slots 64 and the bolts 65, which pass through the plate and the slots and hold the plate in position. By this means 85 any slack in the chains may be taken up. Each of the chains is provided with a pair of inwardly-projected fingers 66, which preferably and as shown are positioned on each chain at diametrically opposite points of the 90 chain, as best shown in Fig. 1. Each of the chains also carries two diametrically opposite projecting pins 67, which are so located on the chains with respect to the fingers 66 that they will operate the escapement device 29 by camming against the outside edge thereof and swing the escapement from the position shown in Fig. 4 to the position shown in Fig. 5 and release a rod, so that it will drop in front of the finger 66 which is in proximity to the pin. 68 100 represents guide-rollers for the chain carried by the frame to prevent the chain being forced away from its path when one of the pins 67 operates the escapement. 69 is a roller provided near each end with the flanges 70 and 105 outside of these flanges with the gears 71 72, the gears 71 72 being secured to the rollers 69. 73 is a pivot carried on the end of the roller which carries the gear 72, and this pivot is journaled in a plate 74, which is provided 110 with the rollers 75. In the end of the roller carrying the gear 71 I provide an ordinary spring curtain-roller construction consisting of the rod 76, which is placed in a centrally-located hole in the end of the roller 69, and 115 to the inner end of this rod is secured one end of a spring 77, the other end of the spring being secured to a part 78, which is free to rotate in the end of the roller. The part 78 has a square projecting end 79, which fits into 120 a slot 80 in a plate 81, which carries at its lower ends the rolls 82. The plates 74 and 81, with their rollers 75 and 82, form a carriage for the roller. By this construction it will be seen that when the roll 69 is rotated in one 125 direction by the gears 71 72 the spring 77 will be put under tension. The roller is mounted in the inclined channel 19, heretofore referred to, with the gears 71 72 in mesh with the racks 20 on the upper side of this channel 130 and the wheels 75 and 82 resting upon the lower side of this channel. The spring 78 is so placed on the rod 76 that when the roller is drawn toward the front end of my machine,

in the manner to be hereinafter described, the spring will be placed under tension, and therefore when the roller is released it will return to a position at the back end of the slot. The slight incline given this slot will aid the roller in returning to its normal position.

Supported in suitable ways 83 are two tables 84 85, upon which the sheets are delivered after they have passed through the drier. Two tables are shown, so that when one is withdrawn for the purpose of taking the sheets therefrom the other will be in position to receive the sheets.

86 is the drive-shaft for the drier, and this shaft is driven in any suitable way, as by means of the belt 87, driven by a pulley 88, which is actuated from any suitable part of the printing or other mechanism, the belt passing around the pulley 89 on the shaft 86. Mounted on the shaft 86 is a gear 90, which is adapted to engage with the gear 91, mounted on the shaft 92, this shaft being the one which carries the sprockets 61, whereby the chains 58 are continuously driven. The gears 90 91 are so proportioned that the chains will be driven at a proper speed in relation to the machine with which the drier coöperates, and in the machine shown in the drawings, in which two fingers 66 are used on the chains, the chain should make one-half a revolution for each sheet delivered to the drier. Also mounted on the shaft 86 is a cam 93.

94 is a lever mounted on the pivot 95 and carrying at one end a cam-roller 96, adapted to bear upon the cam 93, whereby the lever will receive motion therefrom. The lever 94 is in the form of a bell-crank and has an arm 97 extending upwardly from the pivot 95. Mounted in suitable bearings in the arm 97 is a shaft 98, carrying on its inner end a wedge-shape friction gear-wheel 99 and on its outer end a grooved pulley 100.

101 is a grooved pulley loosely mounted on the pivot 95, and 102 is a grooved pulley fast on the shaft 92, which carries the gear 91. 103 is a belt which passes over the grooved pulley 100 and is crossed and then over the guide-pulley 101 and down around the pulley 102, whereby the shaft 98, carrying the wedge-shaped gear 99, is continuously driven.

104 is a shaft mounted in bearings in the side frames 1, and 105 represents a pair of arms through which the shaft loosely passes, so as to support the inner ends of these arms, the other ends being attached to the frame of the printing or other machine in any suitable manner. (Not shown.) Loosely mounted on the shaft 104 between the arms 105 and the shaft-bearings are the arms 106, their free ends being connected together by means of the shaft 107. Fast on the shaft 104 between the arms 105 are the pulleys 108 and 109, and loose on the shaft 107 are the pulleys 110, these pulleys being in line with the pulleys 109 on the shaft 104.

111 represents belts passing over the pulleys 108 and over the pulleys (not shown) car-

ried in the other ends of the arms 105, and on these belts or tapes the sheets are delivered by the press.

112 represents belts or tapes passing around the pulleys 109 and 110.

The tapes 111 constitute a receiving-table to receive the sheets from the press, and the tapes 112 constitute an intermediate table located between the receiving-table and the drier. When the intermediate table is in its lowest position, as shown in Fig. 8, the pulleys 110 are just above the plane of the top shelf in the drier.

113 is an arm projecting upwardly from one of the arms 106 of the intermediate table, and the arm 113 carries at its free end a pin 114, projecting into a slot 115, cut in the end 97 of the lever 94, whereby as the lever 94 is rocked by the cam 93 the outer end of the intermediate table will be raised and lowered.

116 is a grooved friction-gear mounted on the shaft 104 and which is adapted to be driven by the wedge-shaped friction-gear 99 when the lever 94 is in the position shown in Fig. 6, thereby driving the sets of tapes 111 112 to feed a sheet onto a shelf of the drier.

It being remembered that there are two chains 58, two switches 21, two escapement 95 devices 29, and two escapement devices operated by the lever 40, one on each of the side frames and operating on the opposite ends of the rods of the shelves, the operation of each chain, each switch, and each of the two 100 escapement devices being identical with the other one, I will now describe the general operation of my drier. Power being applied to the shaft 86 from any suitable source, as the pulley 88, the chain on each frame will 105 be driven continuously and the chains will move in unison, and at a proper time the projection 67 will strike the side 40 of each of the escapement devices 29 and move each of these devices so that the toe 32 of the leg 30 110 will move from under the lowermost rod 25, while the toe 34 of the leg 31 will move over the lowermost rod and hold the remaining rods 25 in position in the slot 9. The face 35 will then act to force the rod down the slot 9 115 and into the slot 10. At this time the roller 69 will be at the rear end of the slot 19, so that as the rod 25 of the shelf is forced down into the slot 10 the flexible portion 27 of the shelf will pass around the roller 69, which at 120 this time is at the rear end of the slot. The fingers 66 on the chains will now engage each end of the rod 25 and carry the rod toward the front of the machine. Since the pliable portion 27 is looped around the roller 69, 125 this will cause the roller 69 to travel along the channel 19 and through the gears 71 72, engaging the rack 20, and will put the spring in this roller under tension, and this tension will hold the flexible portion 27 taut. In this 130 way the shelf will be peeled out from under the sheet which is carried thereon and the sheet will be dropped onto the receiving-table 84 or 85, depending upon which is in position.

Now as the rod 25 is carried out of the slot 10 and into the slot 8 by the fingers 66 the roller 69 will be drawn along by the flexible part of the shelf until when the roller 25 is 5 nearly at the top of the slot 8 the carriage of the roller 69 will come in contact with the notched end 42 of the levers 40. This will swing the lever 40 and operate the dogs 43 44 in the manner described and will allow the 10 bottom rod 26 of the pile of rods in the slot 17 to drop down into the enlarged portion 18 of the slot. The fingers 66 continue to carry the rod 25 past the end of the slot 8 and into the slot 11, and as the rod 25 is carried along 15 the slot 11 the rod 26 on the other end of the flexible shelf is drawn up the slot 16, as shown in Fig. 1, until when the rod 25 has reached the switches 21 and is in position over the slot 9 the rod 26 will be at the upper end of 20 the slot 15. Now as the fingers continue to move with the chain they will draw the pliable shelf taut, and upon a further movement of the fingers, because of the inclined position which the shelf has at this time, (this position 25 being best shown in Fig. 1,) the rod 25 will, under the influence of the incline 12, slip down the finger 66 and in doing so will depress the switch 21 in the manner shown in Fig. 11 until the rod has passed the end of 30 the switch and is forced into the slot 9, when the switch may move back into its normal position and lock the rod in the channel 9, when the rod will have dropped below the end of the finger. This operation is repeated 35 at each half-revolution of the chain, and each shelf is in succession taken from the bottom of the pile and placed at the top in position to receive a fresh sheet. The cam 93 is so timed that it will drop the table to deliver a 40 sheet, and the movement of the fingers is so timed in relation to the operation of the press that a flexible shelf will be stretched just in time to receive a sheet. Consequently as each shelf is placed in position on the top of 45 the pile a sheet is fed thereon, and this sheet is carried by the shelf which is held taut all the time it is in the pile until the shelf becomes the bottommost shelf of the pile, when in the manner previously described the sheet 50 will be delivered onto the receiving-table. By this construction the sheet is held entirely separate from the adjacent sheets and is given time to thoroughly dry before it is placed on the pile.

55 It is to be of course understood that many other forms of mechanism for feeding the sheet to the drier might be used without departing from the spirit of my invention; but the mechanism which I have described I deem 60 to be peculiarly adapted to be used in connection with my drier. I also desire to have it understood that many changes may be made in the form and mechanical construction of the parts of my device without departing from 65 the spirit of my invention.

It is of course obvious that, if desired, more than a single sheet may be placed side by side

on a shelf or several sheets might be piled one on top of the other on each shelf, and I desire to have it understood that by the term 70 "sheet" used in the specification and claims I mean to include a construction in which this is done.

Having thus described my invention, what I claim as new, and desire to secure by Letters 75 Patent, is—

1. In a drier the combination with a series of pliable shelves arranged in a pile, each adapted to receive a sheet to be dried, of means for holding the shelves taut while in the pile, 80 and means for successively removing and separating the bottom shelf from the pile and transferring it to the top of the pile, in position to receive a fresh sheet.

2. In a drier the combination with a series 85 of pliable shelves arranged in a pile, each adapted to receive a sheet to be dried, of means for holding the shelves taut while in the pile, means for delivering the dried sheet from the bottom shelf of the pile, and means for successively separating the bottom shelf from the pile, and transferring it to the top of the pile in position to receive a fresh sheet.

3. In a drier the combination with a series 90 of pliable shelves, each shelf being adapted to receive a sheet of mechanism for consecutively piling the shelves one on top of the other, means for holding the shelves taut while in the pile, and mechanism for delivering the sheets upon the shelves.

4. In a drier the combination of a series of 95 pliable shelves, each adapted to receive a sheet, of mechanism for consecutively piling the shelves, one on top of the other, and maintaining them in taut condition, mechanism for 100 delivering the sheet from the lowermost shelf and mechanism for separating the bottommost shelf from the pile, and carrying the separated shelf to the top of the pile of shelves.

5. In a drier the combination with a frame 105 having two continuous guides, a pile of shelves, each shelf comprising end rods connected by a sheet of flexible material, the rods at one end of the shelves fitting into one of the continuous guides, and the rods at the 115 opposite ends of the shelves fitting into the other continuous guide, and mechanism for taking the lowermost shelf of the pile and transferring it to the top of the pile.

6. In a drier the combination with a frame 120 having two continuous guides, one of the guides surrounding the other guide, of a pile of shelves, each shelf being composed of end rods connected by a sheet of flexible material the rods at one end of the shelves fitting into 125 one of the continuous guides, and the rods at the opposite ends of the shelves fitting into the other guide, and mechanism for separating a shelf from the bottom of the pile, and transferring it to the top of the pile.

7. In a drier, the combination with a frame 130 having two continuous guides, one of the guides surrounding the other guide, a pile of flexible shelves, each of which is composed of

end rods connected by a sheet of flexible material, the rods at one end of the shelves fitting into one of the continuous guides, and the rods at the opposite end of the shelves fitting into the other guide, and mechanism for separating a shelf from the bottom of the pile without disengaging the rods from the guides, and transferring the shelf to the top of the pile.

8. In a drier the combination with a frame, of a pile of pliable shelves in the frame, a separating device in the path of a portion of the shelves and means coacting with the separating device to automatically operate the same to separate and remove a single shelf from the pile of shelves.

9. In a drier the combination with a frame, of a pile of shelves in the frame, a separating device coacting with a part of a shelf to separate the shelves, one at a time, from the pile; means for automatically actuating the separating device and separate a shelf; mechanism for engaging and removing the shelf after it has been separated from the pile, and mechanism for resetting the separating device.

10. In a drier the combination with a frame, of a pile of pliable shelves in the frame, traveling fingers adapted to act on the end of an individual shelf; means for separating the lowermost shelf from the pile and moving it to a position where it will be engaged by the fingers and means for afterward disengaging the end of the shelf from the traveling fingers.

11. In a drier the combination with a frame having a continuous guide, one portion of which is approximately vertical, a second continuous guide, one portion of which is substantially parallel to the vertical portion of the first-named guide; a pile of shelves, each of which is composed of a flexible portion having a rod at each end, the rods at one end of the shelves standing in the vertical portion of one of the guides, and the rods at the other ends of the shelves standing in the vertical portion of the other guide; means for separating the bottommost shelf from the pile and mechanism for carrying the separated shelf from the bottom to the top of the pile.

12. In a drier the combination with a frame provided with guides, of a pile of flexible shelves carried in the guides; means for separating a shelf from the bottom of the pile; means for carrying a separated shelf to the top of the pile and a switch for disengaging the shelf from its carrying means when the shelf is over the top of the pile.

13. In a drier the combination with a pile of flexible shelves, of a guide for said shelves, said guide having an inclined portion, means for carrying a shelf from the bottom to the top of the pile; means for disengaging the carrying means from the shelf when the shelf has been positioned on top of the pile, said disengaging means consisting of a switch mounted on a pivot and arranged parallel

with the guide and adjacent to the inclined portion thereof and means for normally holding the switch in position.

14. In a drier the combination with a pile of shelves and means for separating the lowermost shelf from the pile said means comprising a pair of toes out of line with each other and means for operating said toes to separate the shelf from the pile.

15. In a drier the combination with a series of flexible shelves, mechanism for feeding a sheet to the top shelf of the pile, mechanism for delivering a sheet from the bottom shelf of the pile and mechanism for presenting each shelf after it has delivered a sheet in position to receive a fresh sheet from the feeding mechanism.

16. In a drier the combination with a pile of pliable shelves, of means for holding the shelves taut while in the pile, mechanism for transferring separately and successively the bottom shelf of the pile to the top of the pile, and mechanism for feeding a sheet onto the shelf which is at the top of the pile.

17. In a drier the combination with a pile of shelves mechanism for removing a shelf from the bottom of the pile and placing it on top of the pile, a rocking feeding mechanism adapted to feed a sheet onto the top shelf of the pile and mechanism for rocking and operating said feeding mechanism as each shelf is placed in position to receive a sheet on top of the pile.

18. In a drier the combination with a plurality of shelves arranged in a pile, of mechanism for removing the lowermost shelf and positioning it above the pile; a feeding mechanism comprising a table formed of belts, and an intermediate table also formed of belts; means for raising and lowering the intermediate table and simultaneously operating the belts of both tables whenever a shelf is placed in position to receive a sheet on top of the pile.

19. In a drier the combination with a series of pliable shelves arranged in a pile, of means for holding the shelves taut while in the pile and means for separating one shelf at a time from the pile and transferring the separated shelf to another portion of the pile.

20. In a drier the combination with a series of pliable shelves arranged in a pile, of means for holding the shelves taut while in the pile, means for feeding sheets to be dried, to the shelves and means for taking the shelves from a pile, delivering the sheets from the shelves and transferring the shelves to the position where they will receive a fresh sheet.

21. In a drier the combination with a series of flexible shelves arranged in a pile each shelf being adapted to receive a sheet; mechanism for separating one end of each shelf from the pile; mechanism for drawing the separated end of the shelf around the other end of the shelf, and mechanism for holding the flexible portion of the shelf taut while the shelf is being so drawn.

22. In a drier the combination with a series of flexible shelves arranged in a pile, each shelf being adapted to receive a sheet; mechanism for separating from the pile one end of the shelf from which a dried sheet is to be delivered; mechanism for drawing the separated end of the shelf around its other end; and mechanism for holding the flexible portion of the separated shelf taut while it is being so drawn; and mechanism for thereafter separating the other end of the shelf from the pile.
23. In a drier the combination with a series of flexible shelves arranged in a pile, means for separating one end of the lowermost shelf of the pile; means for drawing the separated end of the shelf around the other end thereof; and means consisting of a roller provided with a spring for holding the shelf taut while being so drawn; and means for thereafter separating the other end of the shelf from the pile.
24. In a drier the combination with a series of flexible shelves arranged in a pile, each shelf being adapted to receive a sheet; of mechanism for separating the lowermost shelf from the pile, said mechanism comprising a pair of toes out of line with each other; and means for operating said toes to separate the end of the shelf from the pile, and mechanism for carrying the separated end of the shelf around the other end of the shelf; and mechanism for thereafter separating the other end of the shelf from the pile.
25. In a drier the combination with a series of flexible shelves arranged in a pile, of means for separating one end of the lowermost shelf from the pile, and means for carrying the separated end of the shelf around the other end of the pile, and means for separating the said other end of the shelf from the pile, said latter means consisting of a pair of dogs; and means for operating said dogs to separate the end of the shelf from the pile.
26. In a drier the combination with a frame having two continuous guides, one of the guides surrounding the other guide; of a series of shelves each shelf being provided with means at one end of the shelf engaging one of the guides, and means at the other end of the shelf engaging the other guide; and mechanism for moving the end of the shelf guided by the outer guide around the end of the shelf guided by the inner guide.
27. In a drier the combination with a frame provided with a continuous guide substantially rectangular running around the frame, a second continuous guide within the first-mentioned guide; a series of shelves each shelf being composed of end rods connected by a sheet of flexible material, the rods at one end of the shelves fitting into one of the continuous guides and the rods at the opposite ends of the shelves fitting into the other guide, and mechanism for drawing the end of the shelf in the rectangular guide, which is at the bottom of the pile around the end of the shelf in the other guide, and transferring the shelf to the top of the pile.
28. In a drier the combination with a frame having two continuous guides one of the guides being substantially rectangular and the other guide being substantially parallel with one of the sides of the rectangular guide; a series of shelves each shelf being composed of end rods connected by a sheet of flexible material, the rods at one end of the shelves fitting into one of the continuous guides and the rods at the opposite ends of the shelves fitting into the other guide and mechanism for successively moving the ends of the shelves guided in the rectangular guide around the ends of the shelves guided in the other guide.
29. In a drier the combination with a frame having two continuous guides one of the guides being substantially rectangular and the other guide being substantially parallel to one of the sides of the rectangular guide and surrounded by the rectangular guide; of a pile of shelves each shelf being composed of end rods connected by a sheet of flexible material the rods at one end of the shelves fitting into one of the continuous guides, and the rods at the opposite ends of the shelves fitting into the other guide and mechanism for drawing the end of the shelf in the rectangular guide, which is at the bottom of the pile around the end of the shelf in the other guide, and transferring the shelf to the top of the pile.
30. In a drier the combination with a frame having two continuous guides one of the guides being substantially rectangular and the other guide being substantially parallel to one of the sides of the rectangular guide and surrounded by the rectangular guide, of a pile of shelves each shelf being composed of end rods connected by a sheet of flexible material, the rod at one end of the shelves fitting into one of the continuous guides, and the rods at the opposite ends of the shelves fitting into the other guide, and mechanism for drawing the end of the shelf in the rectangular guide which is at the bottom of the pile around the end of the shelf in the other guide, means for holding the shelf taut while it is being so drawn, and means for transferring the shelf to the top of the pile.

Signed by me at Baltimore, Maryland, this 11th day of December, 1902.

ARTHUR K. TAYLOR.
